CONTROL MECHANISM FOR PAPER-MAKING MACHINES

Application filed April 23, 1928. Serial No. 272,255.

This invention relates to mechanism for controlling the thickness of paper while the paper is being made.

In paper making machines heretofore it has been the custom to regulate the thickness of the paper by a "cut and try" system which consisted in opening the gate which supplies paper to the machine to a predetermined point and allowing the machine to run until the paper had passed through the machine where its thickness could be gaged. If the thickness was not that required, the feed gate was readjusted to increase or decrease the thickness of the paper as desired and the paper run through the machine again and its thickness again gaged. As may readily be seen, the gaging of the thickness of the paper could not be done until a long sheet of paper had gone through the machine and if the adjustment was not that desired this strip of paper was wasted. There was no accurate way for predetermining the amount of stock to be fed to the machine in order to make paper of a given thickness. The regulation was purely guess work and as such was far from accurate.

Our device provides gaging means operated by variations in the thickness of the paper for controlling the supply of stock delivered to the machine.

In a patent to Brown, 1,157,204, granted Oct. 19, 1915, is disclosed a machine adapted to control the supply gate by means of a gaging device positioned in the path of travel of the paper. The device shown in this patent, however, sets in motion a motor which starts operation of the feed supply gate and continues to move this gate until the paper has reached sufficient thickness to move the gaging device to another position. In his machine, since the gaging device must be positioned some distance from the supply gate when the control device is operating to increase the thickness of the paper, the paper will be too thick when the last supply stock has reached the gaging rolls, or, if the motor has been operating in the other direction, the paper will have become too thin when the last strip reaches the gaging

rolls. Our device seeks to overcome the defects inherent in a control device of the kind just described by providing impulses to the motor which will cause it to operate only for a predetermined time. If the amount of stock supplied during that period of operation is insufficient the motor will be given another operative impulse until the supply gate has been moved to the right position to supply stock which will make paper of the desired thickness.

The object of our invention, therefore, is to provide a device for gaging and controlling the thickness of the paper being made which will be delicate and sensitive to the slightest changes in the thickness of the paper and which will control the supply of stock to keep the paper within the desired range of thickness.

Referring to the accompany drawings which are made a part hereof and on which similar reference characters indicate similar parts—

Figures 1 and 1^a together present an elevational view of a complete paper making machine using our invention;

Figure 7, a modified detail of the control device.

Numeral 10 indicates the usual stock box in a paper machine from which the stock passes through pipes 11, 12 and 13 to the chambers 14, 15 and 16. Rotatably mounted in the latter chambers are cylinders 17, 18 and 19 which are known as filler cylinders and supply the stock for making the body of the paper. The stock adheres to the periphery of these cylinders and is de-

livered to a felt belt 20 which passes around a series of rollers 21, 22, 23, 24, 25 and 26. A belt 27 passes around rollers 28, 29, 30, 31 and 26.

5 As will be understood by those familiar with machines of this character, the filler cylinders 17 and 19 supply the outside material for the sheet of paper and the cylinder 18 the inside layer which is known in 10 the trade as the filler. A plurality of drums or cylinders 18 may be used if desired to make paper of very great thickness.

15 The film of paper deposited upon the felt belt 20 will pass between the lower surface of this belt and the upper surface of the belt 27 and pass between several series of rolls 32, 33, 34 and 35 from which sufficient of the water in the strip of paper will be 20 squeezed so that the paper may leave the last rolls or presses with sufficient strength to support its own weight. From then on through the machine it passes as a strip of paper 36.

25 Upon leaving the last of the pressing rolls, the strip of paper passes first over a roll 37, thence between rolls 38 and 39 on the gaging device. It then passes around or over drying rolls 40 and between a series of calendering rolls 41 from which it passes to the roll 42 upon which it is wound. If it is desired, of course the paper may be cut into sheets after passing through the calendering rolls instead of being wound 35 on a roll 42. The rolls 41 and 42, the filler cylinders 17, 18, 19 and the heating rollers 40 are all driven from a power shaft 43 through belts 44. In the stock box 10 is provided a gate 45 which may be moved up and down so as to increase or decrease 40 the supply of stock delivered to the cylinders. This gate is operated by means of a motor 46 and mechanism housed in a casing 47. A lever 48 pivoted at 49 on the 45 stock box 10 provides operative connection between the motor and the gate to move the same to open or closed position as will be more fully described. A signal box A has lights therein to indicate the relative thickness of the paper being made; the red light indicating the paper is too thick; the green light that the paper is too thin, and the white light that the thickness is correct.

55 The mechanism so far described is that of the conventional paper making machine with the exception of the gaging rollers 38 and 39. The gaging mechanism and the controlling mechanism comprising our invention will now be more specifically described.

60 The gaging mechanism is shown as a whole at 51 and the control mechanism is shown as a unit at 52. This mechanism, as shown in Fig. 1 of the drawings, is positioned preferably intermediate the last

pressing rolls and the first drying rolls. It will be appreciated therefore that the controlling and gaging devices operate to regulate the stock delivered to the rollers before the film of paper has travelled very far through the machine. This eliminates the great waste incident to gaging the paper after it has passed through the whole machine.

65 The gaging device 51 shown in the right hand end of Fig. 2 will now be described. This device consists of two rollers 38 and 39. The roller 38 is mounted rotatably upon the framework of the machine. The roller 39 is mounted in bearings on an arm 54. This arm is pivotally mounted on a pin 55 and has a short integral arm 58 extending at right angles to the arm 54. An L-shaped arm 59 is pivoted also on the pin 55. A link 60, passing loosely through the end of the arm 58, is attached to the arm 59 at 62. A compression spring 61, surrounding the link 60, is positioned between the arm 58 and a washer 61'. The arm 54 has a rearwardly extending threaded end 56 on which is mounted a weight 57. The arm 59 has on its upper side adjacent the outer end a knife edge 63 adapted to engage a level 65 near the pivot point 64. The lever 65 has also a knife edge 65' which engages the lower side of a lever 66. This lever is pivoted at 66' and has on its outer end rack teeth 67 adapted to engage a pinion 68. A pointer 69 is secured upon the pinion. To give it greater inertia this pointer has a weight 70 secured thereto. The pointer 69 has a downwardly extending end 71 adapted to engage at times with one of the contact points 72, 73 and 74. The arm 71 also carries a post 75 to which a wire in the controlling circuit may be attached as will be later described.

70 From the foregoing description it may clearly be seen that any movement of the roller 39 will be magnified through the levers and arms 54, 59, 65, 66 and rack bar 67 to move the pointer arm 69. If, therefore, a thick strip of paper 36 passes between the rollers, the roller 39 will be raised and through the lever mechanism just described will swing the contact arm 71 to engage the contact 74. If the strip of paper becomes thinner than desired when it passes between the rollers, the roller 39 will drop and, through the magnified motion just indicated, the pointer arm 69 will swing so as to cause the contact arm 71 to engage with the contact 72. The weight 70 provides means for holding the arm 69 against constant oscillation. The spring 61 normally holds the arms 58 and 59 in contact. If chips or small objects pass between the rollers the spring will yield rather than move the weighted pointer arm 69 due to

the inertia of the weight 70. The weight 57 balances the roll 39.

The wiring diagram, which will be later described in detail, is such that when the 5 contact arm 71 is on contact point 73 the white light shown at 136 will be burning and this indicates that paper of the desired thickness is passing through the machine. When the contact 71 is on 74 a red light 188 10 is shown to indicate that the paper passing through the machine is too thick and that the motor 46 will operate to move the stock gate to feed a less supply of stock to the filler cylinders. When the arm swings to 15 contact with 72 a green light 156' is shown indicating that the paper passing through the machine is too thin and that the motor 46 at its next movement will operate to open the stock gate to supply additional stock 20 to the filler cylinders. The above described gaging device would operate the motor 46 continuously when the contact 71 is in engagement with either 72 or 74 except for mechanism about to be described.

25 The mechanism for imparting these operating impulses to the motor will now be described. This mechanism, shown as a whole at 52, is positioned beneath the gaging device just described. It consists of a cam 30 76 operatively connected through a system of gears 37' with the roll 37. This train of gears is arranged so that the cam 76 is driven through one revolution in a time slightly greater than that required for the 35 stock to pass from the box 10 to the rollers 38 and 39. The purpose of this will later be apparent.

An arm 77 is pivoted so as to have its end 40 78 rest upon and engage the outer surface of the cam 76. A deep notch 88' in the underside of the end 78 allows this end of the arm to drop down after the end has passed over the highest point of the cam indicated at 86'. This arm 77 carries a 45 contact point 79 adapted to engage a contact 80 on an arm 81. This latter arm is pivoted at 81' and has a weighted end which rests upon the upper end of a pin or screw 82. An arm 83 screw threaded to 50 the lower end of the pin or screw 82 carries a link 84 to which is pivotally attached a rock arm 85, the said rock arm having made integral therewith a pointer 86 which moves across an indicating dial 87 upon 55 the face 88. The screw 82 is threaded through the sleeve 89 carried by the arm 90. The sleeve 89 has a gear 91 which is engaged by gear 92 on a shaft 93. The shaft 93 has a knob 94 by which it is manually rotated. Rotation of the shaft 93, as may be seen from Fig. 3, will rotate the sleeve 89 so as to move the screw 82 up or down.

60 Rotation of the cam 76 in a counterclockwise direction will cause the end 78 to drop off the point of the cam at each revolution.

When this arm has dropped off, the contacts 79 and 80 are in engagement. These contacts will remain in engagement during the rotation of the cam until the end 78 has been raised so as to break the contact. When the 70 outer end of the arm 81 is in a lowermost position the contact 80 will be positioned up nearer the contact 79 and consequently the contacts 79 and 80 will remain together during the greater part of the rotation of the 75 cam 76. If the end of the arm 81 is raised so as to lower the contact 80, these contacts will be in engagement during only a portion of the rotation of the cam 76. As may be seen from Fig. 3, rotation of the shaft 93 80 will raise or lower the pin 82 on the upper end of which the end of the bar 81 rests. This will vary the length of time which contacts 79 and 80 are engaged during each revolution of the cam 76. Wires 170 and 171 are in circuit with the motor 46 so that when these contacts are closed the motor 46 will be operated, provided of course the contact arm 71 is in engagement with either the contact 72 or 74. The pointed 86 may indicate on the face 87 just the length of time during which the motor will operate during each rotation of the cam 86.

90 In Fig. 7 is shown a modified form of the arm 77. This arm 77' has a cam 78' on its outer end placed opposite to the end 78 and the cam 76' rotates in a clockwise direction. The operation is otherwise the same as that above described.

95 The motor and the mechanism for operating the stock gate will now be described further in detail. The motor shaft has on its outer end a worm 95 which meshes with a worm gear 96 on a shaft 96'. The shaft 96' has a worm 97 on the other end which meshes with a worm wheel 98 on a shaft 99. The shaft 99 has on its upper end a pinion 100 meshing with a gear 101 on a shaft 102. The lower end of the shaft 102 carries a pinion 103 which drives a gear 104. This gear 104 is mounted loosely on a shaft 105 between two collars 106 and 107 which are keyed to the shaft 105. A compression spring 108 surrounding the shaft 105 is positioned between a collar 109 and a gear 110, 105 which latter is also keyed to the shaft. The spring holds the collar 106 in frictional driving engagement with the gear 104 but provides a yielding driving connection between 110 the motor and the shaft.

115 The shaft 105 is threaded through a block 111 which slides on vertical standards 112 positioned in the casing 47. Rotation of the shaft 105 will move the block 111 up or down depending on the direction of rotation. The member 111 also carries an arm 113 which engages stop members 114 and 115 on a vertical rod 116. The upper end of this rod is pivotally attached to a rock arm 116' on a shaft 117'. Another rock arm 120

117² is secured on the other end of the shaft. This latter rock arm extends up and has on its upper end a lug 149' which extends between the ends of pivoted arms 150 and 150' on a limiting switch 117. Wires 149 and 183 connect to arms 150 and 150' respectively. Another wire 151 is connected to a member 151' positioned between the arms 150 and 150'. When the member 113 moves the stops 114 and 115 up or down beyond a predetermined limit the arm 117² breaks contact between the member 151' and either the arm 150' or 150. When the circuit is open between these arms the motor cannot operate, as will be described later.

15 As shown in Fig. 2^a, the limit switch is mounted at the end of the motor 46. The wiring is shown connected to it to the upper right of the motor to more clearly show the 20 construction.

25 The screw shaft 105 has collars 118 and 119 on which are lugs 118' and 119'. These lugs are adapted to strike lugs 111' and 112' on the lower and upper side of the block 111. This will prevent rotation of the shaft 105, the gear 104 sliding between collars 106 and 107. A rod 120, attached to the member 111, extends up through the housing 47 and is attached to the arm 48 through 30 which the stock gate is opened or closed. A shaft 113' has a gear 114' on its inner end which meshes with the gear 110. A hand wheel on its outer end provides manual means for rotating the shaft 105 to move 35 the block 111 up or down as described.

40 Positioned within the housing adjacent the motor is a device for indicating when the motor is actually operating. This consists of a cam 120' on the worm shaft 96' which engages a pivoted arm 121, Fig. 5. Each rotation of the cam will swing the arm 121 to bring the end 191 into contact with 45 190 to close the circuit through wires 192 and 193 with a light 230. When the motor 46 is running signals will be flashed from the light 230.

45 The signalling just described is shown in Fig. 2^a as separate from the motor 46. It is shown in this position to better illustrate 50 the wiring connection.

55 Referring now again to the gaging mechanism shown as a whole at 51, it must be borne in mind that the mechanism must be very sensitive and easily operated. If the contacts between 71 and 72 and 71 and 74 were sufficient to carry high amperage current, it would require good frictional contact between these points and therefore impose a considerable resistance against the 60 movement of the pointer. We have, therefore, provided a system of relays whereby low amperage current may flow through these contacts to suitable relays which will control switches in high amperage lines both 65 to light the signal lights to indicate opera-

tion of the controlling device and to operate the motor 46. This system of wiring with its relays etc. will now be described.

As shown in Fig. 1, A represents a cabinet in which are housed signal lights. B 70 contains relay switches and control devices constituting the electrical wiring for the machine. The system is operated by alternating current entering through the three wires 215, 216 and 217. Wires 216 and 217 are 75 connected to posts 240 and 231 and wire 215 to post 232. These contacts are connected through manually closed switch 233, and wires 234' and 217' to posts 234 and 235 on the distributing plates C. The wire 215 is 80 connected through line 176', switch 176, wire 161 to the center post 236 on the motor 46.

The wiring diagram is as follows: A wire 124 is attached to contact point 73 on the dial of the control device. This wire 124 85 contacts with post 128 on a relay 129. A wire 130 leads from the other side of the relay to a contact post 132 on one of the distributing plates C. A wire 126 attached to contact point 75 on the arm 71 leads to a 90 post 127. When the arm 71 is in contact with the point 73 the circuit through wires 124 and 126 is closed to energize the relay 129 to close the switch 133. When the switch 133 has been closed current may pass 95 through the wire 130 beginning at contact post 132 and passing through the switch 133, wire 134 to the lamp 136 returning through the wire 138 to the post 139. The light 136 is a white light designed to indicate that the arm 71 is in position as shown in Fig. 2 at which time paper of the correct thickness is passing through the machine. When paper of less than the required thickness enters between the rolls 38 and 39 the 100 arm 71 is swung to engage the contact point 72. This closes the circuit between wires 126 and 123. Current therefore may pass beginning at wire 217 thence through contact 105 231, wire 217', distributor plate C, point 127 through the wire 126 to point 75 through the arm 71, contact point 72, wire 123 to a post 140 on the relay 142, thence from the post 141 on this relay, through the wire 143 to wire 130 contact 132 distributor plate C, 110 wire 234', wire 233, contact 240 to wire 216. This circuit energizes the relay 142 to close 115 the switch 144. Current may pass then through wire 130, switch 144, line 145 to contact post 146 on switch 147 and passing through contact point 148 on this switch into line 149. This line connects, as is shown in Fig. 2^a, to contact point on arm 150 on the limit switch 117 and returns through line 151 to the post 152. This circuit being closed, as just indicated, the switch 147 is energized to close switches 120 153, 154 and 155.

Attached to contact points 79 and 80 on the control mechanism 52 are wires 170 and 130

171. The wire 171 leads to a post 173 on an interrupting switch 174. The wire 170 is connected to post 172. The other side of the switch 174 is connected through wire 175 with the binding post 176'. When the contacts 79 and 80 are in engagement, as shown in Fig. 2^a, the circuit is closed through the wiring just indicated to energize the switch 174 and to close the switches 159, 176 and 166. As has been previously described, the contact points 79 and 80 are closed at each revolution of the cam 76. The switch 174 is therefore energized at regular intervals to close the switches just indicated at regular intervals. When the contacts are in engagement the switches are closed and for further description of the wiring diagram we will assume the switch is closed.

The switch 147, being energized, as described above, and the switches 153, 154 and 155 being closed, the circuit is closed through binding post 163 on one of the distributing plates, wire 157, switch 153, wire 158, switch 159, wire 160 to the motor 46, back through wire 167, through switch 166 and wire 165, switch 155, wire 162 to post 164 on one of the distributing plates, to operate the motor. The circuit is also closed through binding post 163, line 157, switch 154, line 156 to the lamp 156' and back through wire 138 to the binding post 139 to light the green light 156'. This light indicates that the paper is too thin and that the motor 46 will next operate to open the stock gate to increase the supply of paper stock to the filler cylinders.

When the contact arm 71 is in engagement with contact point 74, the circuit is closed through wires 126 and wires 125 to energize relay 178 to close the switch 180, the current passing through the circuit as follows: Beginning at point 127 and passing through wire 126 to post 75 through the arm 71, contact point 74, line 125, to the post 177 on the relay 178, returning through line 179, wire 130, to contact point 132. The relay 178 being energized closes the switch 180. The circuit is now closed from contact point 132, through line 130, switch 180, line 181 to the switch 182, line 183 to a post 183' on the limit switch 117, through the line 151 to a contact post 152. This energizes the switch 182 and closes switches 184, 185 and 186. The circuit is then closed from post 163 through line 157, switch 184, line 165, switch 166, line 167, to motor 46, line 160, through switch 159, through line 158, switch 186, line 162 to post 164. It will be seen from the connections just described that posts 163 and 164 are now connected to the motor in reverse order from that described when switches 153 and 155 were closed. This energizes the motor to drive it in an opposite direction from that described when the switch 147 was energized. The circuit

likewise will be closed through line 157, switch 185, line 187 to the red light 188 and thence through line 138. The red light is then burning indicating that the paper is too thick and that the motor will next operate to decrease the supply of stock fed to the filler cylinders.

It will therefore be seen from the foregoing wiring diagram that when contact arm 71 is on contact point 73 a white light is lit, and when the arm is on 72 a green light is lit, and when on contact point 74 a red light is shown, and that the circuits closed through these contacts energize relays to close high power current lines to operate the motor.

As shown at 200, a generator driven from the shaft 43 by means of gears 198 and 199 delivers current through lines 208 and 209 to a tachometer 210. As shown, the generator 200 is geared direct to the shaft which drives the various parts of the paper machine. This tachometer indicates the speed of the paper in feet per minute as it passes through the machine.

At 201 is shown a generator driven through gears 202 and 203 on the shaft which drives operating mechanism for the pump 207, the pump being driven through pulleys 204, 205 and belt 206. The generator 201 delivers current through wires 212 and 213 to a tachometer 214. This tachometer indicates the speed of the pump shaft 209 in revolutions per minute.

While we have shown our device in use on a paper making machine to control the thickness of the paper, it is not our intention that it be limited to this use. It may be adapted for controlling any machine which makes a finished product in sheet form. Any variation in the thickness of the sheet beyond a predetermined standard will operate to control the amount of raw sheet forming material fed to the machine.

It will be obvious to those skilled in the art that various changes may be made in our device without departing from the spirit of the invention, and we, therefore, do not limit ourselves to what is shown in the drawings and described in the specification, but only as set forth in the appended claims.

Having thus fully described our said invention, what we claim as new and desire to secure by Letters Patent, is:

1. In a paper making machine the combination with a stock gate for regulating the amount of stock fed to the machine, of means for operating said gate, means for engaging the paper, electro-responsive means for controlling the operation of said gate operating means, signalling means to indicate when said controlling means is in operation, and safety means limiting the movement of said gate beyond predetermined limits, substantially as set forth.

2. In a paper making machine, the combination with a stock gate for regulating the amount of stock fed to the machine, of means for operating said gate, automatically adjustable means engaging the paper arranged to control the operation of said gate, and means limiting the operation of the said gate to predetermined intervals and predetermined durations, and means for varying the length of time during which the said gate operating means is in operation, substantially as set forth.

3. The combination in a paper making machine of a paper thickness gage mounted to engage the paper at a point in said machine where the paper is sufficiently formed to determine its thickness, means controlled by said gage for changing the amount of paper stock fed to the machine to vary the thickness of the paper, and means operated by the paper for interrupting the operation of said last named means, substantially as set forth.

4. In a paper machine a gaging device adapted to engage the paper and respond to variations in the thickness of the paper passing through the machine, the said device being in control of means for varying the supply of paper stock fed to the machine, and means operated in timed relation with the speed of travel of the paper through the machine for interrupting the operation of said device, substantially as set forth.

5. In a paper making machine having a stock gate for regulating the mount of stock fed to the machine, the combination of means for operating the stock gate, a gaging device responsive to changes in the thickness of the paper for causing operation of said means, and means operated by the strip of paper for interrupting the operation of said means, substantially as set forth.

6. In a paper making machine, means to feed the paper stock thereto, a gage located in contact with the paper at a point in the machine where the thickness of the paper may be determined and movable on changing thicknesses of the paper, electrically operable means for controlling the feed of the paper stock, electrical connections between said gage and said last named means whereby the movement of the gage on changing thicknesses of paper controls said electrical connections to determine the amount of stock fed to the machine, and means operated by the paper for interrupting said connections at regular predetermined intervals, substantially as set forth.

7. In a paper making machine having a stock box with a stock gate and a motor for opening and closing the gate, means operated by changes in the thickness of the paper in control of the said motor to vary the thickness of the paper, and means con-

trolled by movement of the formed paper for limiting the operation of said motor to predetermined intervals and predetermined durations, substantially as set forth.

8. In a paper machine the combination with means for feeding paper stock to the machine of means for engaging the sheet of paper, means operated by said gaging means for controlling the feeding of the stock to the machine in accordance with the thickness of the paper at the engaging means, and means operated by the sheet of paper for limiting the operation of said stock feeding means to predetermined intervals, substantially as set forth.

9. In a paper machine, means for controlling the thickness of the paper comprising a gaging device to determine the thickness of the paper, in control of means to vary the thickness of the paper and said means, and means operated by the paper for limiting operation of the means to vary the thickness of the paper to predetermined intervals and predetermined durations, substantially as set forth.

10. In a paper machine having a stock gate and a motor for operating the same, means for keeping the paper within predetermined limits comprising a gage in contact with the paper and operable when the thickness of the paper overrides prescribed limits, in control of the said motor to vary the thickness of the paper, and means controlled by the movement of the paper for limiting operation of said motor to predetermined durations, substantially as set forth.

11. In a machine for making products in sheet form, a stock gate, a motor for operating the same, means responsive to variations in the thickness of the finished sheet in control of the said motor for varying the amount of sheet forming stock fed to the machine, and means operated by the finished sheet for limiting operation of said motor, substantially as set forth.

12. A machine for making sheet material comprising a stock gate, means for operating the same, means responsive to variations in the thickness of the sheet for controlling operation of the stock gate, and means operated by the sheet for limiting operation of the means for operating the stock gate to predetermined durations, substantially as set forth.

13. In a machine for making sheet products the combination of means responsive to variations in the thickness of the product, with means for varying the amount of sheet forming material fed to the machine, the first named means being in control of the last named means, and means operated by the product passing through the machine for limiting the time during which the

means for operating the feeding means functions, substantially as set forth.

In witness whereof, we have hereunto set our hands and seals at Middletown, Ohio this 18th day of April, A. D. nineteen hundred and twenty-eight.

DARCY E. LEWELLEN.
GRANVILLE R. ZECHER.
